AUXILIARY CRADLE FOR A TELEPHONE HANDSET

William Frank Phillips, Charlotte, N. C.

Application March 31, 1955, Serial No. 35,307

Term of patent 14 years

(Cl. D26—14)

The broken lines shown in Figure 1 are for illustrative purposes only.

I claim:

The ornamental design for an auxiliary cradle for a telephone handset, substantially as shown and described.
